DESIGN FOR A SWITCH BOX

Adolph J. Lippold, Milwaukee, Wis., assignor to
Cherry-Burrell Corporation, Chicago, Ill., a
corporation

Application May 4, 1946, Serial No. 129,328

Term of patent 14 years

(Cl. D26—13)

To all whom it may concern:

Be it known that I, Adolph J. Lippold, a citizen of the United States, residing at Milwaukee, in the county of Milwaukee and State of Wisconsin, have invented a new, original, and ornamental Design for a Switch Box, of which the following is a specification, reference being had to the accompanying drawing, forming part thereof.

In the drawing

Fig. 1 is a plan view of a switch box, showing my new design;

Fig. 2 is a side elevation thereof; and

Fig. 3 is an end elevation thereof.

I claim:

The ornamental design for a switch box, substantially as shown.

ADOLPH J. LIPPOLD.
